UNITED STATES PATENT OFFICE.

CHARLES E. DAVIS, OF CHICAGO, ILLINOIS, ASSIGNOR TO GOODMAN MANUFACTURING COMPANY, OF CHICAGO, ILLINOIS, A CORPORATION OF ILLINOIS.

MINING MACHINE.

Application filed April 22, 1920. Serial No. 375,703.

This invention relates to coal mining machines, and more particularly to mining machines of the type commonly known as the continuous cutter coal mining machine, 5 which are moved laterally along the wall of the mine to cut a horizontal kerf thereunder, and are particularly adapted for use in the room and pillar system of mining.

The principal object of this invention is 10 to provide a new and improved machine of the above description which is capable of use in narrow or thin veins of coal. Further objects will hereinafter appear in the description of the construction and operation 15 of the machine embodying my invention.

As heretofore constructed, coal mining machines of the class described, have been provided with a horizontally disposed cutter bar, having a cutter chain mounted thereon, and a vertically disposed driving sprocket for said cutter chain, driven by a source of power, usually an electric motor. The motor and driving mechanism have been 20 mounted in a plane above the cutter chain and driving sprocket, and a passageway has been provided under the motor to permit the cuttings, or slack, brought rearwardly from the kerf by the cutting chain, to be 25 discharged from the rear of the machine. The slack from the average cut accumulates very rapidly, and unless provided with sufficient space to be properly discharged, is liable to interfere in several ways with the 30 operation of the machine, as for instance, by accumulating in the discharge passage so as to clog or choke the same, or by accumulating in the path of movement of the machine, or by being carried back into the 35 kerf, or cut. Furthermore, it is usually necessary for an operator's helper to shovel away the cuttings as fast as they are ejected from the machine in order to avoid excessive accumulations of slack adjacent the 40 discharge passage. It has been shown, however, that a machine having a motor and passageway arranged as above described, is not adaptable for use in very narrow or thin veins, due to the fact that the overall 45 height of the machine, which is controlled by the total height of the passageway, and the motor mounted thereabove, is too great to be used under such conditions. From 50 a practical standpoint also, it is very diffi-

cult to manually shovel the cuttings while 55 operating in cramped position under a low roof. In the present invention, I provide an improved and novel construction whereby the maximum head-space or clearance of the entire machine is that required by the 60 motor alone. To this end, I place the cutter bar, sprocket and driving mechanism, in front of the motor, and provide a novel means of discharging the cuttings from one 65 side of the machine in such a manner as to minimize accumulations of cuttings in and near the machine, and to reduce the amount of manual labor necessary to keep the discharge passage clear.

The invention consists in the combination, 70 construction, and arrangement of parts as will hereinafter be described in connection with the accompanying drawings, and more particularly defined in the appended claims.

Referring now to the drawings, 75

Figure 1 is a plan view of the machine in cutting position along the wall of the mine.

Figure 2 is a view in elevation of the open side of the machine, that is to say, 80 the side from which the cuttings, or slack, are ejected.

Figure 3 is an enlarged detail plan view of the driving mechanism of the machine.

Figure 4 is an enlarged cross-section of 85 the driving mechanism taken on line 4-4 of Figure 3.

Figure 5 is a transverse cross-section of the machine taken on line 5-5 of Figure 3.

Figure 6 is another transverse cross-section of the machine taken on line 6-6 of Figure 3.

In the drawings, which illustrate one form in which my invention may be embodied, the mining machine comprises a main frame 90 5 and a cutter bar 1 of any approved construction; which is provided with a movable cutter chain 2 made up of suitable chain blocks 3, 3, provided with projecting cutter bits 4, 4, as shown. The main frame 100 5 of the machine comprises a motor 8, mounted in a casing 6, preferably located at the rear end of the machine, and a housing 7, at the front end of the machine. The motor casing 6 and housing 7 form 105 the base plate upon which the machine rests on the mine floor. In order to reduce the overall height of the machine to a minimum,

- I construct the motor casing 5 so as to require a minimum overall height commensurate with the size of a motor having sufficient power for operating the machine.
- 6 The armature of the motor is preferably arranged longitudinally of the machine, as shown by dotted lines in Figure 1. It will be seen that the height of the housing 7 which contains the driving mechanism, is controlled by the height of the motor casing 6. As will hereinafter appear, means are provided for detachably connecting the motor casing 6 to motor casing 7 by means of suitable bolts 9, 9.
- 15 Mining machines of the class described, are fed to the work by means of a flexible draft device, such as a cable, chain, or the like. In the machine illustrated herewith, I have shown a flexible cable 10, which is led around the sheave 11 at the front end of the housing 7, and is anchored at a distance from the machine and near the face of the mine. The cable 10 is wound on a motor-driven drum 12 mounted on the side of the machine. The driving mechanism for said drum will be hereinafter described. By means of the flexible draft gear, arranged as shown, the entire machine is dragged bodily along the face, or wall, of the mine so as to perform the cutting operation in the usual manner. A retarding device is also provided to maintain the machine in its proper cutting relation to the wall. For this purpose, I have shown a friction controlled drum 13 at the rear end of the motor casing carrying a flexible cable 14, which is adapted to be anchored in the direction opposite to that of the feed rope 10, and to be unwound from said drum against friction as the machine advances. It will be understood, however, that any other suitable draft device or propelling mechanism may be used for the purpose of moving and controlling the machine during the cutting operation.
- Referring now more particularly to the novel features of the invention, it will be seen that in Figure 1 the cutter bar 1 is attached to a lug 15 mounted eccentrically of the front end of the machine frame 5, that is to say, to the right of the approximate longitudinal axis of the machine. The cutter chain 2 mounted on said cutter bar, passes rearwardly around the sprocket 16, located in a recess 17, which is formed underneath the housing 7, and opening to one side of said housing, as shown. The bearings and driving mechanism for said sprocket will be hereinafter described. The recess 17 is provided with a lower wall 20, which wall is a continuation of the base plate or face upon which the entire machine rests, and extends laterally under the rear end of the cutter bar, thereby preventing the cuttings or slack from lodging under the base plate of the machine as it is moved along the mine floor. A vertical web 15^a connects the forward edge of wall 20 with the housing 7, and provides a support against which the rear end of said cutter bar abuts. As the machine proceeds to the left along the mine wall, the cutter bits 4, 4 move in the direction indicated by the arrow around the cutter bar 1, and sprocket 16, so as to drag the cuttings out of the kerf into the recess 17. It will be noted that said recess is opened to the following side, that is to say, the side away from which the machine is adapted to move. The cutter bar 1 and cutter chain 2 mounted thereon are arranged so that the forwardly moving section of the latter on the following or right hand side of the cutter bar is adjacent to, and substantially in longitudinal alignment with the following side of the housing 7. This arrangement is clearly shown in Fig. 1. By reason of this construction, the mining machine may be moved into close proximity to the right hand rib or wall, and substantially parallel therewith, when making the initial or sumping cut into the working face. Furthermore, the side margin of the lower wall 20 is arranged so as to approximately coincide with but not extend beyond the cutter chain on the following side of the cutter bar. (See Figure 5.) The arrangement just described, is provided because some of the cuttings are often carried around the sprocket by the chain, without being ejected by the conveyor, and these cuttings fall off of the bottom wall 20 and clear of the machine, instead of accumulating thereon.
- In order to positively eject a large proportion of the cuttings, or slack, which is carried into the recess 17 by the cutter chain 2, I provide a conveyor 21, preferably located transversely of the machine and adapted to move along the inner, or rear end of the recess 17. Details of this conveyor are shown in Figure 6, where it will be seen that it comprises an endless chain, which may be made in any suitable manner, such as comprising links 22, 22, and buckets or paddles 23, 23 intermediate said links. Said conveyor is mounted on, and carried by, a pair of idler sprockets 24, 24, on the left hand side of the machine, and a driving sprocket 25. The driving mechanism of said conveyor is connected to the sprocket 25 and will be described hereinafter in connection with the operation of the other driving mechanism with which it is associated. Bearing plates 22^a, 22^b attached to the housing in any suitable manner, are preferably provided for contact with the moving conveyor 21. I also provide means for tightening said conveyor which comprises a movable member 29, which carries the sprockets 24, 24, and is adjustable in a lateral di-

rection by means of the set screw 30, and the adjustable nut 31, on the left hand side of the machine.

An opening 26, from which the cuttings are ejected by the conveyor 21, is provided on the right side of the machine. This opening is a continuation of the recess 17, but is preferably arranged somewhat above the lower wall 20 of said recess, as shown. This construction allows the conveyor 21 to carry the cuttings upwardly along the inclined surface 27 toward the edge 28 of the opening 26 so as to eject the cuttings at a point above the mine floor and at a distance from the machine so as not to interfere with the continuous operation of the conveyor as the cuttings accumulate. An outwardly extending lip 28^a is provided at the upper edge of the opening 26, in order to deflect the cuttings downwardly as they are thrown from the machine.

Referring now to the driving mechanism for operating the machine, it will be seen that the motor has operative connection with three driving elements, namely, the feed rope drum 12, the cutter chain sprocket 16, and the conveyor chain sprocket 25. Details of the driving mechanism are shown in Figures 3, 4 and 5.

The motor 8 is provided with a driving shaft 32, extending thru the wall 34 of the motor casing 6, as shown in Figure 4, and having an annular bearing member 32^a, mounted in a suitable aperture 7^b in the housing 7. A bevel gear 33 is mounted on the end of said shaft. A ring 35 is seated in an annular recess 34^a formed in the casing wall 34, said ring being also adapted to fit the aperture 32^b in which the bearing member 32^a is carried, so as to maintain the shaft 32 in proper alignment with its bearings in the motor casing, and also with its driving connections in the housing 7. By means of this arrangement, the entire motor casing, with the bearing member 32^a and the bevel gear 33, may be quickly detached and removed rearwardly from the housing 7, when the bolts 9, 9, are removed.

The bevel gear 33 is meshed with a bevel gear 36, pivoted on a vertically disposed pin 37. Said pin 37 is mounted at the lower end on the housing 7 and at the upper end in the cover plate 7^a of said housing. A suitable bearing sleeve 38 and thrust bearing plates 39, 39, are provided for the bevel gear 36. A second bearing pin 40 is arranged adjacent said first mentioned pin 37, and parallel therewith. Said pin 40 is mounted at the upper end in the cover plate 7^a of the housing 7, and extends downwardly thru the lower wall of the housing 7, and is mounted at its lower end in the boss 19, integral with the lower wall 20 of the machine. Said bearing pin 40 carries a hub member 43 which extends downwardly and

is connected with the cutter chain sprocket 16. Suitable bearing sleeves 44 and 45 are provided for said hub member and sprocket. An annular gear member 41 is loosely mounted on the upper end of said hub, and is driven by the pinion 42 of the bevel gear 36, before mentioned. A clutch 46 is interposed between the gear member 41 and the hub, which clutch comprises suitable recesses on said gear member, which are adapted to be engaged by radially extending lugs 47, 47, carried by a vertically movable sleeve 48, feathered to said hub member 43. The sleeve 48 is adapted to be shifted by any suitable mechanism, such as a yoke 49^a, a shifter arm 49, (see Figure 4) carried by a transverse rocking arm 50, and a control lever 51 on the outside of housing 7.

The gear member 41 is also provided with a downwardly extending hub portion 52, carrying a worm gear 53 keyed thereto by means of a key 54. Bearing sleeves 55 and 56 are provided at the upper and lower ends of said gear hub 52, as shown. A thrust bearing ring 57 is mounted on an annular supporting member 58, provided with an arcuate lower surface adapted to fit in a socketed bushing 59, seated in the bottom wall of the housing 7, as shown. The construction just described, provides a self-centering seat for the thrust bearing 57, which automatically adjusts itself to wear on the main bearings 44 and 45.

The mechanism for driving the feed drum comprises the worm gear 53 before mentioned, which drives the worm wheel 60, and shaft 61, extending thru the side wall of the housing 7. A pinion 62 is mounted on said shaft, and engages a gear 63 associated with the change-speed mechanism 64. The change speed mechanism may be of any construction desired, but I prefer to utilize a friction-released planetary gear mechanism of a well-known type, as it lends itself readily to the purpose and uses of the machine. Details of this planetary gear need not be explained, excepting to call attention to clutch jaws 65 and 66 which provide a high-speed and a low-speed connection, respectively, thru the planetary gearing in the usual manner. These jaws are adapted to be engaged and disengaged by a clutch member 67, carried by an endwise movable shifter rod 67^a. In the preferred construction shown, the shifter rod 67^a is keyed to the pinion 68 and rotates therewith. A yoke 67^b carried by a reciprocating arm 67^c is provided to move said rod into its various positions. The movement of the arm 67^c is preferably controlled from the rear of the machine, by means of the bell-crank 67^d, control rod 67^e and operating lever 67^f. Any suitable driving connection may be made between the pinion 68 and the feed drum 12, as for instance, by means of gears

69 and 70. The friction band 64^a of the planetary gear, may also be controlled from the rear of the machine by means of control connections 64^b and 64^c, as shown in Figure 1.

5 The driving mechanism for operating the conveyor 21, comprises a vertically disposed shaft 71, located in the housing 7. Said shaft carries a gear 72, which meshes with, 10 and is driven from, the gear member 41 before described. A mitre gear 73 moves with said gear 72, and has a driving connection with a second mitre gear 74 carried by the conveyor driving shaft 76, which extends 15 thru a partition 77 of the housing and carries thereon the conveyor sprocket 25. The use and operation of my invention is as follows:

20 The machine is moved laterally along the face of the mine by means of the flexible cable 10 which is wound on the feed drum 12, in the usual manner already described. The cuttings are brought out of the kerf by the cutter chain 2, and are carried into the 25 recess 17. Most of the cuttings are dislodged as the chain sweeps around the sprocket and are deposited in the recess. As the cuttings accumulate, they are swept rearwardly into the conveyor 21, and are 30 carried thereby upwardly and out of the discharge passage 26. The conveyor may be moved at any speed desired, but I find that best results are obtained by operating the conveyor at sufficient speed to discharge the 35 cuttings at a considerable distance from the machine. A pile of cuttings will therefore be formed in a line with the discharge passage, but as the machine is continually moved laterally away from the pile, the cuttings 40 cannot accumulate in sufficient amount to clog the discharge passage.

45 It is necessary to avoid an excessive accumulation of cuttings along the right hand side of the chain, so that they will not be carried back into the kerf. As has been before pointed out, the bottom wall 20 of the recess 17, does not extend beyond the line of movement of the cutter chain, so that the cuttings cannot accumulate on the 50 margin of this wall, but fall away and clear of the chain as the machine is moved laterally.

55 Another feature of my invention is the arrangement in which the cutter bar extends eccentrically from the front end of the frame, i. e., at one side of the approximate longitudinal center line thereof. This construction is provided so as to establish the approximate center of gravity of the machine in advance of the cutter bar, whereby 60 the machine tends to maintain its cutting position adjacent the floor of the mine, particularly when advancing a kerf over a slightly rolling or uneven mine floor. In the present construction, this object is attained by providing the longitudinal axis,

or center line B—B of the electric motor in advance of the longitudinal axis of center line A—A of the cutter bar as shown in Figure 1.

70 While I have shown and described herein a specified construction as an embodiment of my invention, it will be understood that many variations in construction will readily suggest themselves to those skilled in the art, without departing from the spirit and 75 scope of my invention.

Having described my invention, what I claim as new and desire to cover by Letters Patent, is:

1. In a room and pillar mining machine 80 the combination of an elongated frame, a cutting element extending eccentrically from one end of said frame with one side thereof in substantially longitudinal alignment with and opened to the adjacent side of the machine frame, and means for moving said machine in a general longitudinal direction into the mine face and thereafter advancing said machine laterally along said face with said cutting element at the following side of 85 said machine.

2. In a mining machine adapted to be moved laterally along the face of a mine wall, the combination of an elongated frame, a cutting element extending eccentrically 95 from one end of said frame adjacent the following side thereof and means for discharging the cuttings from said following side of the machine.

3. In a mining machine adapted to be 100 moved laterally along the face of a mine wall, the combination of a frame, having a recess in the forward portion thereof, closed to the advance side of said machine, a cutting element adapted to move the cuttings 105 into the front end of said recess, and means independent of said cutting element for discharging the cuttings from the following side of the machine.

4. In a mining machine adapted to be 110 moved laterally along the face of the mine wall the combination of a frame having a recess on the front portion thereof closed to the advance side of said frame, a cutting element adapted to move cuttings into said 115 recess, means independent of said cutting element for discharging the cuttings from the following side of the machine, and a motor located rearwardly of said recess having operative connection with said cutting element and said discharging means.

5. In a mining machine adapted to be 120 moved laterally along the face of the mine wall, the combination of a frame having a recess in the front portion, provided with a discharge passage opening to the side of the machine opposite to the direction in which the machine is adapted to move, a cutting element adapted to move the cuttings into said recess, means independent of 125 130

1 said cutting element for ejecting the cuttings from said discharge passage, and a motor located rearwardly of said recess, having operative connection with said cutting element and said ejecting means.

6. In a mining machine adapted to be moved laterally along the face of the mine wall, the combination of an elongated frame having a recess therein, a cutting element 10 extending longitudinally from a point near the base of said frame, and adapted to move cuttings into said recess, and means in said recess for discharging said cuttings from one side of the frame at a point above the plane of said cutting element.

7. In a mining machine adapted to be moved laterally along the face of the mine wall, the combination of a frame, a cutting element extending horizontally from said frame near the base thereof, and adapted to move the cuttings into a recess in said frame, means in said recess for discharging the cuttings at a point above the plane of said cutting element, and a motor located 20 rearwardly of said recess and said cutting element, having operative connection with said cutting element and said discharging means.

8. In a mining machine adapted to be moved laterally along the face of a mine wall, in combination, a motor, a casing for said motor, a housing detachably connected to said motor casing and forming therewith the bottom plate upon which the machine is 30 moved on the mine floor, said housing being provided with a recess having a discharge passage opening to the following side thereof, a cutting element extending forwardly from the end of said housing opposite said motor casing, and in a plane above the lower wall thereof, said cutting element being adapted to move the cuttings into said recess, means in said recess for discharging the cuttings therefrom, and mechanism in 35 said housing having driving connection with said motor, and affording operative connection with said cutting element and said discharging means.

9. In a mining machine adapted to be moved laterally along the mine wall, the combination of an elongated frame having a recess closed to the advance side and opening to the front end and to the following side of said machine, a cutter arm extending 40 eccentrically from the front end of said frame forwardly of said recess, an endless cutter chain movably supported on opposite sides of said arm and movable rearwardly into and forwardly out of said recess, the 45 forwardly moving section of said cutter chain being in substantial longitudinal alignment with the lateral boundary of the machine frame at the following side thereof.

65 10. In a mining machine adapted to be

moved laterally along the face of a mine wall, the combination of a frame having a recess in the front portion thereof provided with a horizontally disposed lower wall, said recess opening to the front end 70 and to the following side of said frame, an endless cutting element supported to move rearwardly into and forwardly out of said recess, said forwardly moving section extending laterally beyond the side margin 75 of said lower wall.

11. In a mining machine adapted to be moved laterally along the face of a mine wall, the combination of a frame having a recess in the front portion thereof provided 80 with a horizontally disposed lower wall, said recess opening to the front end and to the following side of said frame, an endless cutting element supported to move rearwardly into and forwardly out of said 85 recess, said forwardly moving section extending laterally beyond the side margin of said lower wall, and means in said recess for discharging the cuttings from the following side of the machine. 90

12. In a mining machine adapted to be moved laterally along the face of a mine wall, the combination of a frame having a recess in the front portion provided with a lower wall, said recess opening to the front 95 end and to the following side of said frame, an endless cutting element supported to move rearwardly into and forwardly out of said recess, said forwardly moving portion thereof extending laterally beyond the side 100 margin of said lower wall, and a motor located rearwardly of said recess having operative connection with said cutting element.

13. In a mining machine adapted to be moved laterally along the face of a mine wall, the combination of a frame having a recess in the front portion thereof provided 105 with a horizontally disposed lower wall, said recess opening to the front end and to the following side of said frame, an endless cutting element supported to move rearwardly into and forwardly out of said recess, the forwardly moving portion thereof extending laterally beyond the side margin of said lower wall, means in said recess for discharging the cuttings from the following side of the machine, and a motor located rearwardly of said recess having operative connection 110 with said cutting element and said discharge means. 120

14. In a mining machine adapted to move laterally along the face of a mine wall, the combination of a frame having a recess in the front portion provided with a horizontally disposed lower wall, said recess opening into the front end and following side of said frame, a cutter bar extending longitudinally from the forward end of said frame, a cutter chain supported on said 125 frame. 130

6 cutter bar and movable rearwardly along one side thereof into the front end of said recess, thence around a driving sprocket in said recess and thence forwardly along the opposite side of said cutter arm, the forwardly moving section of said cutter chain extending laterally beyond the margin of said lower wall, a motor having operative connection with said driving sprocket and a casing for 10 said motor mounted rearwardly of said frame and forming therewith the bottom plate upon which the machine is moved on the mine floor.

15. In a mining machine adapted to be moved laterally along the face of a mine wall, the combination of a horizontally disposed motor, a casing for said motor, a frame mounted forwardly of said casing, and having a recess opening to the following side thereof, said casing and frame forming the bottom plate upon which the machine is adapted to slide on the mine floor, a cutter arm extending from the forward end of said frame, a cutter chain carried by said cutter arm, a sprocket for said chain mounted in said recess, a winding drum having an axis extending transversely of the machine and mounted on the advance side of said frame, said cutter chain sprocket and said winding drum each having operative connection with 30 said motor.

16. In a mining machine, in combination, a body portion comprising a motor casing having a horizontally disposed motor and a frame member mounted forwardly of said casing, said casing and frame member forming the base plate upon which the machine is adapted to be moved on the mine bottom, a cutter arm provided with a cutter chain extending longitudinally from the front or wall end of said frame, a motor driven winding drum mounted on one side of said frame with its axis extending transversely of the machine, gearing on said frame operatively connecting said motor with said cutter chain and said drum, a flexible feeding element, associated with said drum, a guide for said feeding element adjacent the front end of said frame and flexible retarding means extending from the rear of said motor casing.

50. 17. In a mining machine, in combination, a body portion comprising a motor casing having a motor, and a frame member mounted forwardly of said motor casing and forming therewith the bottom plate upon which the machine is adapted to move on the mine bottom, said frame having a recess in the forward end thereof, a cutter arm extending from the forward end of said frame and provided with a cutter chain, a sprocket for said cutter chain mounted in said recess, a shaft connected with said sprocket and extending above said recess, a gear member loosely mounted on said shaft, speed reduction gearing interposed between

said motor and said gear member, and clutch means affording driving connection between said gear member and said shaft.

18. In a mining machine, in combination, a body portion comprising a motor casing 70 having a motor and a frame member mounted forwardly of said motor casing and forming therewith the bottom plate upon which the machine is adapted to move on the mine bottom, said frame having a recess in the forward end thereof, a cutter arm extending from the forward end of said frame and provided with a cutter chain, a sprocket for said cutter chain mounted in said recess, a shaft connected with said sprocket and extending above said recess, a gear member loosely mounted on said shaft, speed reduction gearing interposed between said motor and said gear member, clutch means affording driving connection between said gear member and said shaft, a winding drum 80 mounted on one side of said frame with its axis extending transversely of the machine, speed reduction gearing interposed between said gear member and said winding drum, and clutch means associated with said speed reducing gearing affording driving connection at will between said gear member and said winding drum.

19. In a mining machine adapted to be 85 moved laterally along the face of a mine wall, the combination of a frame having a recess in the forward portion thereof closed to the advance side and opened to the front end and following side of said machine, a cutter bar extending longitudinally from the forward end of said recess, a driving sprocket in said recess, a cutter chain supported on said cutter bar and engaging said sprocket, a motor located rearwardly of said recess 105 having operative connection with said driving sprocket, and a casing for said motor adapted to rest on the mine floor.

20. A mining machine slidable on a mine bottom comprising a cutter chain carrying cutter bar extending longitudinally thereof during lateral cutting, a motor whose height substantially determines the height of the machine located in rear of the rear end of said chain and operatively connected thereto, and means for feeding said machine laterally including feed operating means disposed on a horizontal axis in front of said motor and operated thereby and flexible feeding portions acting on the opposite ends of the machine frame.

110. 21. A mining machine slidable on a mine bottom comprising a cutter chain carrying cutter bar extending longitudinally thereof during lateral cutting, a motor whose height substantially determines the height of the machine located in rear of the rear end of said chain and operatively connected thereto, and means for feeding said machine laterally including a feed operating member 115

operatively connected to said motor and rotatable on an axis disposed horizontally on said machine and on the advancing side thereof in front of said motor and flexible feeding portions acting on the opposite ends of the machine frame.

22. A mining machine slidable on a mine bottom and comprising a front frame portion, cutting mechanism including a cutter bar disposed longitudinally of said portion during lateral cutting, lateral feeding mechanism including a feed operating member carried on the advancing side of said frame portion on a transverse axis, a plurality of flexible feeding portions, and directing means for said portions including a guide rotatable on a vertical axis in front of said member, and a motor connected to said portion and disposed in rear of said bar and member and connected to said cutting mechanism and feed operating member, said motor and bar being so disposed that the height of the former substantially determines the height of the machine.

23. The combination with a mining machine slidable on its bottom on a mine bottom, of cutting mechanism including a cutter carrying bar projecting at one end of said machine, lateral feeding mechanism including a feed operating member rotatable on an axis extending transversely of the same end of the machine and cooperating flexible feeding means, and a motor operatively connected to said cutting mechanism and feed operating member and disposed at the opposite end of said machine.

24. The combination with a mining machine slidable on its bottom on a mine bottom, of cutting mechanism including a cutter carrying bar projecting at one end of said machine, lateral feeding mechanism including a feed operating member rotatable on an axis extending transversely of the same end of the machine and cooperating flexible feeding means, and a motor operatively connected to said cutting mechanism and feed operating member and disposed at the opposite end of said machine, said motor and feed operating member being so disposed that the axis of the latter is below the top of the motor.

25. The combination with a mining machine slidable on its bottom on a mine bottom, of cutting mechanism including a cutter carrying bar projecting at one end of said machine, lateral feeding mechanism including a feed operating member rotatable on an axis extending transversely of the same end of the machine and cooperating flexible feeding means, and a motor operatively connected to said cutting mechanism and feed operating member and disposed at the opposite end of said machine, said motor and feed operating member being so disposed that the top of said feed

operating member is substantially within the vertical limits of said motor.

26. The combination with a mining machine slidable on its bottom on a mine bottom, of cutting mechanism including a cutter carrying bar projecting at one end of said machine, lateral feeding mechanism including a feed operating member rotatable on an axis extending transversely of the same end of the machine and cooperating flexible feeding means, a motor operatively connected to said cutting mechanism and feed operating member and disposed at the opposite end of said machine, and cuttings agrees means at the machine end of said bar.

27. A mining machine comprising a feed and cutter frame section and a motor-carrying frame section located in alinement therewith, said sections being operatively connected to form a rigid structure, the maximum height of which is substantially the height of said motor frame section, lateral feeding mechanism including flexible feeding means and a feed operating member rotatable by said motor on a transverse axis disposed below the top of said second mentioned section, and cutting mechanism driven by said motor and disposed at the same end of the machine as said feed operating member including a cutter bar disposed in horizontal planes intersecting the motor.

28. A mining machine comprising a feed and cutter frame section and a motor-carrying frame section located in rear thereof, said sections being operatively connected to form a rigid structure slidable on its bottom on a mine bottom, the maximum height of which is substantially the height of said motor frame section, lateral feeding mechanism including flexible feeding means and a feed operating member rotatable by said motor on a transverse axis and disposed below the top of said second mentioned section, and cutting mechanism driven by said motor including a cutter bar disposed during lateral cutting longitudinally of said sections in a horizontal plane above the machine bottom and rigidly connected between said first mentioned section and the machine bottom.

29. The combination in a mining machine slidable on its bottom on a mine bottom, of cutting mechanism including a cutter carrying bar projecting at one end of said machine, of lateral feeding and guiding mechanism operating to feed said bar transversely, said mechanism including a feed operating member rotatable on an axis extending transversely of the machine, a cooperating guiding member disposed closely adjacent the front end of the machine and to the face being cut, and cooperating flexible feeding means acting on the opposite ends of the machine including a flexible feeding portion extending from said feed

operating member around said guiding member and laterally therefrom, and of a motor operatively connected to said cutting mechanism and feed operating member and disposed between both said cutting mechanism and said feed operating member and the opposite end of the machine.

30. The combination in a mining machine 70
slidable on its bottom on a mine bottom, of
10 cutting mechanism including a cutter chain
carrying cutter bar projecting at one end
of said machine and a cutter chain sprocket
at the inner end of said bar, of lateral feed-
ing and guiding mechanism operative to feed
15 said bar along a face, said mechanism in-
cluding a feed operating member rotatable
on an axis substantially lying in a plane
parallel with the face and not nearer the
face than the sprocket axis, a cooperating
20 guiding member disposed closely adjacent
the front end of the machine and to the face
being cut, and cooperating flexible feeding
means acting on the opposite ends of the
machine including a flexible feeding portion
25 extending from said feed operating member
around said guiding member and laterally
therefrom, and of a motor operatively con-
nected to said sprocket and feed operating
member and disposed between both said
30 sprocket and said feed operating member
and the opposite end of the machine.

31. The combination in a mining machine 85
slidable on its bottom on a mine bottom, of
35 cutting mechanism including a cutter chain
carrying cutter bar projecting at one end of
said machine and a cutter chain sprocket at
the inner end of said bar, of lateral feed-
ing and guiding mechanism operative to feed
40 said bar along a face, said mechanism in-
cluding a feed operating member rotatable
on an axis extending parallel with the face
and transversely of the machine and dis-
posed on the advance side of the machine
45 and on the same side of the axis of said
sprocket, a cooperating guiding member dis-
posed closely adjacent the front of the ma-
chine on the advance side thereof, flexible
feeding means acting on the opposite ends
50 of the machine including a flexible feeding
portion extending from said feed operating
member around said guiding member and
laterally therefrom, and of a motor operat-
ively connected to said sprocket and feed
55 operating member and disposed between said
sprocket and said feed operating member
and the opposite end of the machine.

32. The combination in a mining machine 90
slidable on its bottom on a mine bottom, of
60 cutting mechanism including a cutter chain
carrying cutter bar projecting at one end of
said machine and a cutter chain sprocket at
the inner end of said bar, of lateral feeding
and guiding mechanism operative to feed
65 said bar along a face, said mechanism in-
cluding a feed operating member on the ad-

vancing side of the machine rotatable on
an axis extending parallel with the face
and transversely of the machine and dis-
posed in a plane in rear of a parallel plane
including the axis of said sprocket, a co-
75 operating guiding member disposed in front
of said last mentioned plane and closely
adjacent the front end of the advancing side
of the machine, and cooperating flexible
feeding means acting on the opposite ends
80 of the machine including a flexible feeding
portion extending from said feed operating
member around said guiding member and
laterally therefrom, and of a motor oper-
atively connected to said sprocket and feed
85 operating member and disposed between said
sprocket and said feed operating member
and the opposite end of the machine.

33. The combination in a mining machine 95
slidable on its bottom on a mine bottom, of
90 cutting mechanism including a cutter chain
carrying cutter bar projecting at one end
of the machine and a cooperating cutter
chain driving sprocket, of feeding and
guiding mechanism operative to feed said
95 machine along a face when said bar projects
into the face, said mechanism including a
feed operating member rotatable during cut-
ting along the face on an axis not nearer
the face than the axis of said sprocket, a
100 flexible feeding member cooperating with
said feed operating member and disposable
in a single strand connection to a fixed
point in juxtaposition to the face and in
advance of the machine, and a guiding mem-
105 ber for said flexible feeding member so
disposed adjacent the point where the bar
projects from the machine and so cooperat-
ing with said flexible member between the
feed operating member and said point of
110 fixation as to direct said flexible member
along the face from substantially the point
from which the bar projects from the ma-
chine and to said point of fixation in a
path extending substantially parallel to and
115 closely adjacent to the face, and of a motor
operatively connected to said sprocket and
feed operating member and disposed between
the opposite end of the machine and the
portion thereof carrying said sprocket and
120 feed operating member.

34. The combination in a mining machine 125
slidable on its bottom on a mine bottom, of
120 cutting mechanism including a cutter chain
carrying cutter bar projecting at one end
of the machine and a cooperating cutter
chain driving sprocket, of feeding and
guiding mechanism operative to feed said
125 machine along a face when said bar projects
into the face, said mechanism including a
feed operating member rotatable during cut-
ting along the face on an axis disposed in
rear of a plane parallel to the face and
including the sprocket axis, a flexible feed-
ing member cooperating with said feed
130

operating member and disposable in a single strand connection to a fixed point in juxtaposition to the face and in advance of the machine, and a guiding member for said flexible feeding member so disposed between the feed operating member and the point where the bar projects from the machine and so cooperating with said flexible member between the feed operating member and 5 said point of fixation as to direct said flexible member along the face from the point from which the bar projects from the machine and to said point of fixation in a path extending substantially parallel 10 to and closely adjacent to a face, and of a motor operatively connected to said sprocket and feed operating member and disposed between the opposite end of the machine and the portion thereof carrying said sprocket and feed operating member.

35. The combination in a mining machine 15 slideable on its bottom on a mine bottom, of cutting mechanism including a cutter chain carrying cutter bar projecting at one end of the machine and a cooperating cutter chain driving sprocket, of feeding and guiding mechanism operative to feed said machine along a face when said bar projects into the face, said mechanism including a feed operating member rotatable during cutting along the face on an axis disposed parallel to the plane of the bar and in a plane 20 parallel to the face and located on said axis on the advancing side of the sprocket axis, a flexible feeding member cooperating with 25 said feed operating member and disposable in a single strand connection to a fixed point in juxtaposition to the face and in advance of the machine, and a guiding member for said flexible feeding member so disposed between the feed operating member and the point where the bar projects from the machine and so cooperating with said flexible member between the feed operating member and 30 said point of fixation as to direct said flexible member along the face from the point from which the bar projects from the machine and to said point of fixation in a path extending substantially parallel 35 to and closely adjacent to the face, and of a motor operatively connected to said sprocket and feed operating member and disposed between the opposite end of the machine and the portion thereof carrying said sprocket and feed operating member.

36. The combination in a mining machine 40 slideable on its bottom on a mine bottom, of cutting mechanism including a cutter chain carrying cutter bar projecting at one end of said machine and a cooperating cutter chain driving sprocket, of feeding and guiding mechanism operative to feed said machine along a face when said bar projects into the face, said mechanism including a feed operating member rotatable during 45

cutting along the face on an axis parallel to the face and the plane of said bar, a flexible feeding member cooperating with said feed operating member and disposable in a single strand connection to a fixed 50 point in juxtaposition to the face and in advance of the machine, and guiding means for said flexible member including a guiding member so disposed relative to said feed operating member and so cooperating 55 with said flexible member between the feed operating member and said point of fixation as to direct said flexible feeding member along the face to said point of fixation substantially in a plane parallel to and adjacent the face and including the point from which the bar projects, and of a motor operatively connected to said sprocket and feed operating member, said motor and all 60 of said previously mentioned elements being 65 so disposed that the height of the machine is substantially the height of said motor.

37. The combination in a mining machine 70 slideable on its bottom on a mine bottom, of cutting mechanism including a cutter chain carrying cutter bar projecting at one end of the machine and a cooperating cutter chain driving sprocket, of feeding and guiding mechanism operative to feed said machine along a face when said bar projects 75 into the face, said mechanism including a winding member, a flexible feeding member 80 cooperating with said winding member and disposable in a single strand connection to a fixed point in juxtaposition to the face and in advance of the machine, and a guiding member for said flexible member disposed adjacent said winding member and the point where the bar projects from the machine, said winding member and said 85 cutter chain driving sprocket rotating on axes lying substantially within a plane disposed parallel to the face during cutting along the latter and said guiding member being disposed between said plane and the 90 face, and a motor operatively connected to said sprocket and winding member and disposed between the opposite end of the machine and the portion thereof carrying said 95 sprocket and winding member.

38. In a mining machine, the combination 100 of an elongated frame having a cuttings discharge channel in the forward end thereof opening to one side of said frame, an endless cutting element supported by said frame 105 and having its rear end disposed in said channel, a motor, driving connections for said cutter chain, and feed operating means to move said mining machine laterally on its bottom along a mine floor, said feed means including a planetary gearing having a portion thereof extending below the upper boundary and to one side of said cuttings channel.

39. In a mining machine, the combination 110

- of an elongated frame having a cuttings discharge channel in the forward end thereof opening to one side of said frame, an endless cutting element supported by said frame and having its rear end disposed in said channel, a motor disposed rearwardly of the rear end of said cutting element and having driving connections therewith, and feed operating means to move said mining machine laterally on its bottom along a mine floor, said feed means comprising a planetary gearing mechanism disposed on a transverse axis having a portion thereof extending below the upper boundary and on the closed side of said cuttings channel.
- 15 40. In a mining machine, the combination of an elongated frame having a cuttings discharge channel in the forward end thereof opening to one side of said frame, an endless cutting element supported by said frame and having its rear end disposed in said channel, a motor, driving connections for said cutter chain, and feed operating means to move said mining machine laterally on its bottom along a mine floor, said feed means including gearing having a portion thereof extending below the upper boundary and to one side of said cuttings channel.
- 20 45. In a mining machine, the combination of an elongated frame having a cuttings discharge channel in the forward end thereof opening to one side of said frame, an endless cutting element supported by said frame and having its rear end disposed in said channel, a motor disposed rearwardly of the rear end of said cutting element, driving connections for said cutter chain, and feed operating means to move said mining machine laterally on its bottom along a mine floor, said feed means including gearing having a portion thereof disposed outside 50 of said channel and extending below the upper plane of said cutting element.
- 25

41. In a mining machine, the combination

of an elongated frame having a cuttings channel in the forward end thereof, an endless cutting element supported by said frame and having its rear end disposed in said channel, a motor disposed rearwardly of the rear end of said cutting element and having driving connections therewith, and feed operating means to move said mining machine laterally on its bottom along a mine floor, said feed means including gearing having a portion thereof extending below 40 the upper boundary and to one side of said cuttings channel.

42. In a mining machine, the combination of an elongated frame having a cuttings channel in the forward end thereof, an endless cutting element supported by said frame and having its rear end disposed in said channel, a motor disposed rearwardly of the rear end of said cutting element, driving connections for said cutter chain, and feed operating means to move said mining machine laterally on its bottom along a mine floor, said feed means including gearing having a portion thereof disposed outside 55 of said channel and extending below the upper plane of said cutting element.

CHARLES E. DAVIS.
